(57) CLAIM

The ornamental design for a coin display holder for the fifty statehood quarters, as shown and described.

DESCRIPTION

FIG. 1 is a front elevational view of a coin display holder for the fifty statehood quarters showing my new design, the undisclosed sides and rear are not part of the claimed design;

FIG. 2 is an enlarged view of a representation of the state flag of Delaware and the corresponding coin slot showing the flag in greater detail for clarity of illustration of FIG. 1.

FIG. 3 is an enlarged view of a representation of the state flag of Pennsylvania and the corresponding coin slot showing the flag in greater detail for clarity of illustration of FIG. 1.

FIG. 4 is an enlarged view of a representation of the state flag of New Jersey and the corresponding coin slot showing the flag in greater detail for clarity of illustration of FIG. 1.

FIG. 5 is an enlarged view of a representation of the state flag of Georgia and the corresponding coin slot showing the flag in greater detail for clarity of illustration of FIG. 1.

FIG. 6 is an enlarged view of a representation of the state flag of Connecticut and the corresponding coin slot showing the flag in greater detail for clarity of illustration of FIG. 1.

FIG. 7 is an enlarged view of a representation of the state flag of Massachusetts and the corresponding coin slot showing the flag in greater detail for clarity of illustration of FIG. 1.

FIG. 8 is an enlarged view of a representation of the state flag of Maryland and the corresponding coin slot showing the flag in greater detail for clarity of illustration of FIG. 1.

FIG. 9 is an enlarged view of a representation of the state flag of South Carolina and the corresponding coin slot showing the flag in greater detail for clarity of illustration of FIG. 1.

FIG. 10 is an enlarged view of a representation of the state flag of New Hampshire and the corresponding coin slot showing the flag in greater detail for clarity of illustration of FIG. 1.

FIG. 11 is an enlarged view of a representation of the state flag of Virginia and the corresponding coin slot showing the flag in greater detail for clarity of illustration of FIG. 1.

FIG. 12 is an enlarged view of a representation of the state flag of New York and the corresponding coin slot showing the flag in greater detail for clarity of illustration of FIG. 1.

FIG. 13 is an enlarged view of a representation of the state flag of North Carolina and the corresponding coin slot showing the flag in greater details for clarity of illustration of FIG. 1.
